UNITED STATES PATENT OFFICE

92,701

DESIGN FOR A CELLOPHANE HAT OR ANALOGOUS ARTICLE

Creta Coffey, Chicago, Ill., assignor to Nu-Dell
Manufacturing Co. Inc., a corporation of
Illinois

Application May 21, 1934, Serial No. 51,858

Term of patent 3½ years

To all whom it may concern:

Be it known that I, Creta Coffey, a citizen of the United States, residing at Chicago, in the county of Cook and State of Illinois, have invented a new, original, and ornamental Design for a Cellophane Hat or Analogous Article, of which the following is a specification, reference being had to the accompanying drawing, forming a part thereof.

Fig. 1 is a plan view of my new, original and ornamental cellophane hat,

Fig. 2 is a side elevational view showing the same as it would be in position upon the head of a wearer, and

Fig. 3 is a front view of the hat shown in Fig. 2, showing the appearance of the same as it would be upon a wearer looking from the front.

What I claim is:

The ornamental design for a cellophane hat or analogous article, as shown and described.

CRETA COFFEY.
